SAFETY CATCH

Eugene Morehouse, Providence, R. I., assignor to
 B. A. Ballou & Co., Inc., a corporation of Rhode
 Island

Application March 3, 1943, Serial No. 477,828

5 Claims. (Cl. 24—157)

This invention relates to a finding member for a safety catch, more particularly to an inside rotor for the safety catch.

The safety catch of the type having two outside ears with a rotor between those ears is usually provided with a slot in the ears of the outside member and also a slot in the inside member, which slots when in registry receive a pin stem and move out of registry for the locking of the pin stem in the catch. It is usual to slot both the outside and inside member with a cutting tool at one time after the parts have been assembled. In my prior Patent No. 2,221,429, dated November 12, 1940, I have illustrated one means of providing slots in these members without using a cutting tool after assembly. It is not desirable in many instances to provide a strip of stock of the width necessary to provide the rotor member in a single piece as shown in this patent and accordingly a different construction is provided and different steps in the method of production.

One of the objects of this invention is to provide the rotor member in two separate individual parts and then assemble these parts just prior to the time when they are positioned into the outside piece or stationary part of the catch. The stationary part of the catch holding them in assembled relation.

Another object of the invention is to provide a rotor member formed of individual parts sufficiently thin so that each may be slotted by punching and thereafter assembled into finished form with the construction such that the parts will remain in a certain registered relation.

Another object of this invention is to provide an arrangement and formation of parts with the use of a minimum amount of stock having such shape that it may be made by press operations.

With these and other objects in view, the invention consists of certain novel features of construction, as will be more fully described and particularly pointed out in the appended claims.

In the accompanying drawings:

Fig. 1 is an elevation of the safety catch complete and in open position;

Fig. 2 is an end view thereof;

Fig. 3 is a section on substantially line 3—3 of Fig. 1;

Fig. 4 is a plan view of one part of the rotor member;

Fig. 5 is an edge view thereof;

Fig. 6 is a plan view of the other part of the rotor member;

Fig. 7 is an edge view thereof, this figure and

Figure 5 being in the relation that they bear one to the other but spread apart;

Fig. 8 is a perspective view of the parts shown in Figs. 6 and 7;

Fig. 9 is a perspective view of the parts shown in Figs. 4 and 5;

Fig. 10 is a perspective view showing the parts in Fig. 8 and Fig. 9 brought together in assembled relation;

Fig. 11 is a sectional view of the outside part of the safety catch;

Fig. 12 is a sectional view showing the rotor and outside part in assembled relation;

Fig. 13 is a top plan view of a strip of stock showing the different operations as performed thereon in proceeding with the construction of one part of the rotor member;

Fig. 14 is a sectional view on line 14—14 of Fig. 13;

Fig. 15 is a top plan view of a strip of stock showing the initial different steps in the formation of the companion part of the rotor member;

Fig. 16 is a sectional view through the center of the showing in Fig. 15;

Fig. 17 is a sectional view of the part formed as shown in Fig. 16 detached from the strip;

Fig. 18 is a plan view of the separate part of Fig. 17; and

Fig. 19 is a sectional view after a further operation has been performed.

In carrying forward this invention I cut out from two separate narrow sheets or ribbons of stock the two parts of the rotor member which are to be assembled together. One part is so shaped as to have a recess in it while the other part has a projection to interlock with this recess to prevent relative rotation of the parts one with another. Each of the parts is slotted or an opening is punched in the sheet stock and a drawing

occurs to cooperate with this punched slot prior to the cutting of the piece from the sheet of stock. Thereafter such cutting or blanking is merely necessary to assemble the two cut-out pieces together and position them between the ears for

the completion of the catch. The ears serve to hold the two pieces in assembled relation. The interlocking parts serve to retain the parts in registry one with the other while so held. The drawing, embossing or deflecting of the stock is termed in the trade as "dapping" or the result of this step "dapped," and I use these terms in this sense herein.

With reference to the drawings, 20 (see Fig. 13) denotes a strip or ribbon of sheet stock from which one part of the rotor is formed, while 21

denotes a strip or ribbon of sheet stock from which the companion part of the rotor is formed. The first operation upon the strip stock 20 is a punching or cutting out of an opening 22. The strip is then advanced to the next station where a dapping, drawing or embossing operation is formed to provide a cup designated 24 by drawing the stock at the location about the end of the slot in suitable tools for the purpose. The opening 22 will be so shaped that after distortion by drawing it will arrive at its proper shape. At the next station a severing operation is formed along the line 25 to remove from the sheet of stock one of the individual and separate pieces which is to be assembled with another piece to form the rotor member and at this same time form the notch 23.

For the companion part of the rotor I use the strip 21 which at the first station is punched out to provide an opening 26. At the second station a dapping operation is performed to draw, dap, or emboss the stock as at 27 similar to the operations performed on the strip 20. At the next station the part is severed from the strip along the line 30 being illustrated as removed from the strip at 31 in Fig. 17. As the severing operation occurs along the line 30 a finger 28 (see Fig. 19) is formed extending therefrom. This part lodges on a transfer plate and is moved to a location where, by an operation between dies the finger 28 is bent upwardly at right angles as shown in Fig. 18 while at the same time a finger 29 is sheared from the stock of the part 31 and bent to the position shown in Fig. 18. The parts formed from the strips of stock 20 and 21 are illustrated individually in plan view in Figs. 4 and 6 wherein there is a disc-like portion 32, handle 33 and slot 34 which are the same in each of the pieces. These two pieces of Figs. 4 and 6 are placed in face to face contact with hollow trunnion portions 24 and 27 extending in opposite directions (see Figs. 8, 9, and 10) and with the slots 34 in registry and the handles 33 in registry. This registered relation is maintained by reason of the recess 23 in the parts shown in Fig. 4 and the finger 28 extending into this recess as shown in Fig. 10 while a finger 29 is of the size to engage the edges of the two handles which are spaced apart and assists in locking the parts against relative rotation.

The outside body member of the safety catch consists of a base portion 40 with two upstanding ears 41 and 42 which are slotted as at 43 and recessed as at 44 to provide bearings for the trunnions 24 and 27. The assembly as shown in Fig. 10 is positioned between the ears with the trunnions 24 and 27 in recesses 44 and then the ears brought into vertical relation as shown in Figs. 2 and 3 so as to hold the two-part assembly as shown in Fig. 10 while the handles 33 extend outwardly between the ears for the manipulation or rotation of the rotor in the body.

In the showing in Fig. 12 recesses 44' are shown as extending completely through the ears 41 and 42 so that the outer ends of the trunnions 24 and 27 would be visible on the outer surface of the catch. After the catch is assembled as shown in Figs. 1-3 or 12 the base is soldered onto a

suitable support in a position to receive, and retain or lock the pin stem in position.

From the above it will appear that I have eliminated the necessity of bending of integral halves, which is one of the operations performed in my patent above-referred to, and substituted therefor the placing of two parts face to face in assembled relation at the time of positioning the rotor member between the ears of the body, the parts which lock the two members against relative rotation being formed at the time of cutting and shaping of the parts during the other necessary operation upon them. The two ears of the body member effectively prevent separation of these two parts and the tying of them together as afforded by the folding is unnecessary.

I claim:

1. An inside rotor member for a safety catch to be positioned between two ears comprising two individual sheet stock pieces each slotted with their slots in registry and each cylindrically dapped with their dapped portions extending in opposite directions and interlocking parts between said pieces to prevent relative rotation of said pieces.

2. An inside rotor member for a safety catch to be positioned between two ears comprising two individual sheet stock pieces each slotted and provided with a handle with their slots and handles in registry and each dapped with their dapped portions extending in opposite directions to provide bearing trunnions for relative rotation and interlocking lugs and recesses respectively on said pieces to prevent relative rotation of said pieces.

3. An inside rotor member for a safety catch to be positioned between two ears comprising two individual sheet stock disc shaped pieces each slotted and provided with a radially extending handle, said pieces being so related that their slots and handles are in registry and each dapped with their dapped portions extending in opposite directions to provide bearing trunnions for relative rotation and interlocking lugs and recesses respectively on said pieces to prevent relative rotation of said pieces.

4. An inside rotor member for a safety catch to be positioned between two ears comprising two individual sheet stock disc shaped pieces each slotted and provided with a handle radially extending with their slots and handles in registry and each dapped with their dapped portions extending in opposite directions to provide bearing trunnions for relative rotation and interlocking lugs and recesses respectively on said pieces to prevent relative rotation of said pieces.

5. A safety catch comprising a body having spaced ears with bearing recesses therein, a rotor member in the space between said ears comprising two individual sheet stock pieces each slotted with their slots in registry and each dapped with their dapped portions extending in opposite directions into said bearing recesses to be held by said ears in assembled relation and interlocking lugs and recesses respectively on said pieces to prevent relative rotation of said pieces.

EUGENE MOREHOUSE.
